(57) CLAIM

The ornamental design for a cover for game controller, as shown and described.

DESCRIPTION

FIG. 1 is a front, bottom perspective view of a cover for game controller, showing my new design;

FIG. 2 is a front, top, left perspective view thereof;

FIG. 3 is a front, top, right perspective view thereof;

FIG. 4 is a front view thereof;

FIG. 5 is a left view thereof; and,

FIG. 6 is a right view thereof.

The broken lines shown in the figures are for the purpose of illustrating portions of the cover for game controller, which form no parts of the claimed design.

1 Claim, 6 Drawing Sheets
